DESIGN FOR A CALENDAR STAND OR SIMILAR ARTICLE

Howard L. Moore, Cochranton, Pa.

Application November 17, 1944, Serial No. 116,402

Term of patent 7 years

(Cl. D74—5)

To all whom it may concern:

Be it known that I, Howard L. Moore, a citizen of the United States, residing at Cochranton, in the State of Pennsylvania, have invented a new, original, and ornamental Design for a Calendar Stand or Similar Article, of which the following is a specification, reference being had to the accompanying drawing, forming part thereof.

Figure 1 is a front elevation of a calendar stand or similar article, showing my new design.

Figure 2 is a top plan view, and

Figure 3 is an end or side elevation.

I claim:

The ornamental design for a calendar stand or similar article, as shown.

HOWARD L. MOORE.
